HOT WATER SUPPLY SYSTEM

John T. Muller, Nutley, N.J., Edgar D. Hodgson, Jr., Salt Lake City, Utah, and Bernard H. Bremer, Allendale, N.J., assignors to Leslie Co., Lyndhurst, N.J., a corporation of New Jersey

Filed Apr. 8, 1966, Ser. No. 541,201
3 Claims. (Cl. 126—362)

This invention relates to hot water supply systems including a hot water heater and a hot water storage tank and, more particularly, to an improved hot water supply system which permits the direct supplying of hot water to the demand whenever the demand is within the capacity of the heater regardless of the temperature of the water in the storage tank.

In hot water heating systems it is conventional to provide for short duration peak demands by augmenting the hot water from a limited heater capacity with hot water which has been heated and stored in a relatively large storage tank. It is important in such systems to relate the demand time to the storage capacity. Also, after a sustained peak demand, it is a common experience to have the storage tank filled with cold water so that, for a period of time, only cold water is available to the system from the storage tank.

We have now devised a circuit for a hot water supply system in which no water is taken from the storage tank as long as the demand is within the heater's capacity, in which the demand requirements above the heater's capacity are handled jointly by the heater and the storage tank, and in which excess heater capacity during periods of low demand or no demand is utilized to heat the water in the storage tank. The hot water supply system of the present invention includes a hot water heater, a hot water storage tank, a cold water supply line having a branch communicating with the heater and another branch line communicating with the storage tank, and a hot water supply line having a branch line communicating with the heater and another branch line communicating with the storage tank. Pursuant to the invention, a spring-loaded check valve is positioned in the cold water branch line to the storage tank and operable to permit flow therethrough to the tank when the pressure in the tank is reduced by the demand to a level representative of the maximum heating capacity flow rate of the heater, and a by-pass reverse-flow circuit is connected across the spring-loaded check valve in the aforesaid cold water branch line. The by-pass circuit includes a circulating pump operable in response to a water temperature in the storage tank below a predetermined storage temperature and further includes a check valve disposed to permit flow from the pump through the by-pass line only in a direction opposite to the direction of flow of cold water through the spring-loaded check valve. In particularly advantageous embodiment of the invention, a two-line parallel flow circuit is positioned in the by-pass line with a fixed flow-rate valve in one line and with a controllable flow rate valve in the other line. A control element is further provided for the aforesaid controllable flow-rate valve responsive to a pressure drop in the hot water supply line and adapted to close the valve when there is substantially no demand on the hot water supply line.

These and other novel features of the hot water supply system of the invention will be more readily understood from the following description taken in conjunction with the accompanying drawings in which:

FIG. 1 is a schematic diagram of a hot water heating system embodying the invention; and

FIG. 2 is a schematic diagram of another embodiment of the invention in a hot water heating system.

2

In the hot water heating system shown in FIG. 1, a cold water supply line 5 is provided with two branch lines, one branch line 6 being connected to a hot water heater 7 and the other branch line 8 being connected to a hot water storage tank 9. A hot water supply line 10 is connected by one branch line 11 to the output of the heater 7 and by another branch line 12 to the output side of the hot water storage tank 9. The hot water heater 7 and the hot water storage tank 9 are thus connected in parallel between the cold water supply line 5 and the hot water supply line 10.

In order to limit the flow of hot water from the storage tank 9 to the hot water supply line 10 only when the demand for hot water exceeds the heating capacity of the heater 7, the cold water supply branch line 8 is provided with a spring-loaded check valve 13 set so as to open only when the pressure drop in the hot water supply line, felt back to the delivery side of the check valve 13, corresponds to a hot water demand rate in excess of the heating capacity flow-rate of the heater 7. When the demand thus exceeds the capacity flow rate of the heater, the pressure drop across the check valve 13 is sufficient to open the valve and permit cold water to flow through the branch line 8 into the storage tank 9. Flow of water into the tank permits flow of hot water from the tank through the hot water branch line 12 to join the hot water flowing through the other hot water branch line 11 to satisfy the demand in the hot water supply line 10.

When the demand in the hot water supply line 10 is not sufficient to open the check valve 13 and permit hot water to flow from the storage tank to join the output from the heater, provision is made for some of the hot water output from the heater to flow in the opposite direction through the hot water branch line 12 and into the storage tank. This is accomplished by providing a by-pass line 14 across the spring-loaded check valve 13 arranged to effect flow in a direction opposite to that through the check valve 13. The by-pass line 14 contains a circulating pump 15 and a check valve 16 which permits flow through the line 14 only in the aforementioned direction. Accordingly, when the spring-loaded check valve 13 is closed, the circulating pump draws water from the storage tank 9 through the line 14 and into the cold water branch line 6 to the heater. This flow of water from the storage tank to the heater is accompanied by a corresponding flow of hot water into the storage tank from the heater through the lines 11 and 12. Thus, whenever the demand for hot water is not at a peak level such as to open the spring-loaded check valve 13, some of the hot water output from the heater 7 will be diverted to the storage tank 9 regardless of whether there still exists a moderate demand or no demand in the hot water supply line 10. It is presently preferred to control the circulating pump 15 with a temperature sensor 17 in the storage tank circulation line 14 so as to stop the circulation of hot water between the heater 7 and the storage tank 9 when the temperature in the storage tank reaches a predetermined level. In addition, the heater 7 and the hot water supply line 10 can be provided with a feed-back sensor connection, shown as a dotted line 18 in FIG. 1, pursuant to conventional heating systems provided with temperature regulations.

65 The modification of the heating system of the invention shown in FIG. 2 differs from that shown in FIG. 1 in two respects: the heater circuit enclosed in the broken line 20 is substantially that described and claimed in application Ser. No. 317,265, filed Oct. 18, 1963, now Patent 70 No. 3,232,336, and the hot water circulation line 14 is provided with a two-line parallel flow circuit between the cir-

culating pump 15 and the check valve 16. In the heater circuit enclosed by the broken line 20, the heater 7 comprises a heat exchanger supplied with steam through a steam control valve 21 and having a condensate outlet. The hot water output from the heater 7 passes through a blending valve 22 in which the hot water is mixed with cold water from a bypass line 23 in proportions controlled by an element such as a differential diaphragm 24. The diaphragm 24 is responsive to the difference in pressure between the cold water supply line 6 (through line 23) and the demand hot water supply line 10 (through line 11). Movement of the diaphragm 24 is transmitted through a mechanical linkage 25, for example, to the blending valve 22, and this movement of the linkage 25 is arranged to develop a signal output from an interconnected conventional signal generating device 26. The output from this generator, which is therefore proportional to the hot water demand, is transmitted through a connection 27 to the steam control valve 21 so that steam is supplied to the heat exchanger in proportion to the demand for hot water.

In the storage tank circulating line 24 in FIG. 2, the parallel flow circuit comprises two lines 28 and 29. One line, such as line 28, is provided with a fixed flow-rate valve or orifice 30, and the other line 29 is provided with a variable flow control valve 31. The two lines 28 and 29 can be discrete lines as shown in FIG. 2 or the line 28 can be formed as an integral by-pass in the valve 31. The output of the signal generating device 26, which is connected to the steam supply valve 21 as aforementioned, is also advantageously connected to the variable flow control valve 31 through a connection 32, so that maximum output from the generating device 26 closes the variable flow control valve 31. Alternatively, the valve 31 can be a spring-loaded check valve such as valve 13 in FIG. 1, in which case the spring-loaded diaphragm of the check valve, with its connections to opposite sides of the valve, provides the control element for controlling operation of the valve in response to a pressure drop in the hot water supply line.

In operation of the system shown in FIG. 1, a demand for hot water in the hot water supply line 10 is met solely by hot water from the heater 7 up to a rate equal to its heating capacity. When the demand exceeds this capacity, the pressure drop across the spring-loaded check valve 13 is sufficient to open the valve. The flow of cold water through the valve 13 into the storage tank 9 permits hot water to flow out of the tank through the line 12 and thus augment the flow of hot water into the supply line 10. The circulating pump 15, sensing cool water adjacent the circulating line 14, will operate to short-circuit cold water back to the branch line 6 to the heater, but by limiting this flow to about 10% of that through the line 8 this short-circuiting has little effect on the ability of the storage tank to supply hot water to the demand line 10. When the hot water demand does not exceed the capacity of the heater and the spring-loaded check valve 13 is closed, the circulating pump 15 draws water from the storage tank through the by-pass line 14 and delivers it through the cold water branch line 6 to the heater. The flow of water from the storage tank into the circulating line 14 causes hot water to flow into the storage tank through the hot water branch line 12 so that there is established a circulating flow of water from the storage tank to the heater and back to the storage tank until the temperature of the water leaving the tank is high enough to actuate the sensor

17 and shut off the circulating pump 15. In this way, the system operates to build up a full supply of hot water in the storage tank whenever the storage tank supply is not being used to meet a peak demand exceeding the heater capacity.

The operation of the system shown in FIG. 2 is essentially the same as that in FIG. 1. However, the variable flow rate valve 31 is closed whenever the hot water demand is at a peak so that the short-circuited water from the storage tank to the cold water branch line 8 is limited to that which can pass through the relatively low fixed flow-rate orifice 30. Whenever the hot water demand does not exceed the heater capacity, the signal supplied by the generating device 26 will be insufficient to hold the valve 31 fully closed and this will permit the valve 31 to permit a higher rate of flow of water from the storage tank to the heater and back to the storage tank through the hot water branch line 12. As in the system shown in FIG. 1, this permits the hot water supply in the storage tank to be built up whenever the hot water demand is within the capacity of the heater to supply. As a consequence, the storage tank is ready to supply hot water at peak demand rates at more frequent intervals than has been possible with prior art hot water heating systems.

25 We claim:

1. In a hot water supply system including a hot water heater, a hot water storage tank, a cold water supply line having a branch line communicating with the heater and another branch line communicating with the storage tank, 30 and a hot water supply line having a branch line communicating with the heater and another branch line communicating with the storage tank, the improvement which comprises a spring-loaded check valve positioned in the cold water branch line to the storage tank and operable to 35 permit flow therethrough to the tank when the pressure in the tank is reduced by the demand to a level representative of the maximum heating capacity flow rate of the heater, and a by-pass reverse-flow circuit connected across the spring-loaded check valve in said cold water branch 40 line, the by-pass circuit including a circulating pump operable in response to a water temperature in the storage tank below a predetermined storage temperature and a check valve disposed to permit flow from the pump through the by-pass line only in a direction opposite to 45 the direction of flow of cold water through the spring-loaded check valve.

2. A hot water supply system according to claim 1 in which the by-pass reverse-flow circuit includes a two-line parallel flow circuit positioned in the by-pass line with a 50 fixed flow-rate valve in one line thereof and with a controllable flow rate valve in the other line thereof, and a control element for said controllable flow rate valve responsive to a pressure drop in the hot water supply line and adapted to close the valve when there is no demand 55 on the hot water supply line.

3. A hot water supply system according to claim 1 in which the two-line parallel flow circuit is integrally formed in a single valve having a fixed-flow rate orifice and a controllable flow rate valve connected in parallel.
